(57) **CLAIM**

The ornamental design for a housing for packaging machines and parts thereof as shown and described.

DESCRIPTION

The patent or application file contains at least one drawing executed in color. Copies of this patent or application with color drawing(s) will be provided by the Office upon request and payment of the necessary fee.

FIG. 1.1 is a front view of a housing for packaging machines and parts in accordance with a first embodiment of the design.

FIG. 1.2 is a rear view thereof.

FIG. 1.3 is a right side view thereof.

FIG. 1.4 is a left side view thereof.

FIG. 1.5 is a top view thereof.

FIG. 1.6 is a bottom view thereof.

FIG. 1.7 is a perspective view of a front, a top, and a left side thereof.

FIG. 3.1 is a front view of a housing for packaging machines and parts in accordance with a second embodiment of the design.

FIG. 3.2 is a rear view thereof.

FIG. 3.3 is a right side view thereof.

FIG. 3.4 is a left side view thereof.

FIG. 3.5 is a top view thereof.

FIG. 3.6 is a bottom view thereof.

FIGS. 1.1-1.7: A first embodiment of a housing of a packaging machine. FIGS. 3.1-3.6: A second embodiment of a housing of a packaging machine. The dash-dash broken lines shown in the drawings illustrate portions of the housing of the packaging machine and form no part of the claimed design. The dash-dot-dash broken lines illustrate symbolic breaks in the housing of the packaging machine length. The appearance of any portion of the article between the dash-dot-dash broken lines forms no part of the claimed design.

(Continued)

The red portions identify the color of the columns. The capped portions of the columns in dark gray form no part of the claimed design.
